(57) **CLAIM**

The ornamental design for a soft-sided container with triangular ventilation panels, as shown and described.

DESCRIPTION

FIG. 1 is a perspective view of the soft-sided container with triangular ventilation panels;

FIG. 2 is a front view of the soft-sided container with triangular ventilation panels;

FIG. 3 is a back view of the soft-sided container with triangular ventilation panels;

FIG. 4 is a first end view of the soft-sided container with triangular ventilation panels;

FIG. 5 is a second end view of the soft-sided container with triangular ventilation panels;

FIG. 6 is a top view of the soft-sided container with triangular ventilation panels; and,

FIG. 7 is a bottom view of the soft-sided container with triangular ventilation panels.
